Primary Examiner — Jennifer L Watkins*Assistant Examiner* — John Patrick G Ribay(74) Attorney, Agent, or Firm — Select IP Law Corporation; Ashkon Cyrus(57) CLAIM

The ornamental design for a jacket, as shown and described.

DESCRIPTION

FIG. 1 is a front view of a jacket showing my design; FIG. 2 is a back view thereof.

FIG. 3 is a left side view thereof.

FIG. 4 is a right side view thereof; and,

FIG. 5 is a top view thereof.

The broken lines showing a zipper toggle and zipper track depict environment and form no part of the claim. The broken lines showing the remainder of the jacket are for environmental purposes only and form no part of the claimed design.
